UNITED STATES PATENT OFFICE.

CHARLES O. SHEPHERD, OF NEW YORK, N. Y.

FOLDING CRATE OR BOX.

1,323,109.

Specification of Letters Patent. Patented Nov. 25, 1919.

Application filed March 19, 1919. Serial No. 283,467.

To all whom it may concern:

Be it known that I, CHARLES O. SHEPHERD, a citizen of the United States, residing at New York city, in the county of New York 5 and State of New York, have invented new and useful Improvements in Folding Crates or Boxes, of which the following is a specification.

This invention relates to shipping boxes 10 or crates and has for its object the provision of a container so constructed that the component parts thereof may be easily and quickly folded to occupy but little space for convenience in transportation or storage.

15 An important and more specific object is the provision of a folding crate or box in which the ends and partitions are foldable to lie flat upon the bottom or upon one another and in which the sides include 20 panels similarly hinged to lie upon the folded ends and partitions and further including strips hingedly connected with the top and bottom formation and hinged at their centers for inward collapsing whereby 25 the top frame may be disposed directly upon the bottom frame whereby to provide a structure which will occupy the minimum space.

A further object is the provision of a 30 device of this character in which the ends are held in extended position by securing members carried by the top frame, the sides being prevented from collapsing by the extended ends and also held by securing members.

An additional object is the provision of a 35 folding container of this character which will be simple and inexpensive in manufacture, highly efficient and extremely convenient in use, durable in service, and a general improvement in art.

With the above and other objects and advantages in view, the invention consists in the details of construction to be hereinafter 40 more fully described and claimed, and illustrated in the accompanying drawings, in which—

Figure 1 is a perspective view of the crate in extended position.

45 Fig. 2 is a longitudinal sectional view therethrough,

Fig. 3 is a cross sectional view,

Fig. 4 is a side elevation of the crate in folded position,

50 Fig. 5 is a longitudinal sectional view therethrough, and

Fig. 6 is a cross sectional view.

Referring more particularly to the drawings, the bottom of the device is shown as 60 rectangular shape and is formed of a bottom proper 10 having its edges provided with strips or flanges 11 and 12 which may be secured together and effectively braced by corner members 13. This structure constitutes what might well be called the bottom 65 frame.

The top frame comprises end and side strips 14 and 15, respectively, suitably secured together by corner braces 16. Hinged, as shown at 17, upon the upper edge of one 70 of the side strips 15, is the cover 18 which carries at its edges depending wire members 19, for a purpose to be described.

The ends of the container are designated by the numeral 20 and these ends are hinged, 75 as shown at 21, upon the bottom proper 10 and are adapted to be disposed against the inner faces of the strips 12 and 14 of the bottom and top frames, respectively. Turn buttons 22 are pivoted upon the faces of the 80 end strips 14 and are engageable over the upper edges of the ends 20 for holding the ends against folding movement. If preferred, a partition 23 may also be hinged upon the bottom 10, as shown at 24. Any 85 desired means may be employed for holding the partition in vertical position.

Each of the sides is formed as a panel 24^a hinged at its lower edge, as shown at 24^b, upon the side strips 11 of the bottom frame. 90 These panels are foldable inwardly in the same manner as the ends 20 and are held in extended position by turn buttons 22, also the same as the ends 20. It will further be observed that the panels 24^a are disposed 95 outwardly of the ends 20 and will also be prevented from collapsing or folding by their engagement with the ends. Each side further includes corner and center strips each formed in two sections 25 and 26 which are hingedly connected at their meeting edges, as shown at 27, and which are hingedly connected with the side bars 15 and 11 of the top and bottom frames, respectively, as shown at 28 and 29.

100 When the container is in extended or set up condition, the parts are arranged as shown in Figs. 1 to 3, inclusive, that is the ends 20 are disposed in vertical position and have their upper edges engaged by the turn 110 buttons 22. This position of the ends holds the sides against inward movement, as will

be obvious. The cover 18 is secured in position upon the top frame by engagement of the depending wires 19 thereon with coöperating screw eyes, or the like, 30, carried by one of the side strips 15. The end strips 14 may have secured thereon, if desired, handles 31 by means of which the crate may be very easily handled.

When it is desired to collapse the container, it is first necessary that the operator disengage the wires 19 from the screw eyes 30 and swing the cover 18 upon its hinges 17, after which the turn buttons 22 are disengaged from the ends 20 and the ends 20 are swung inwardly toward each other and onto the bottom 10. The turn buttons 22 holding the side panels 24^a are then turned, after which the side panels are swung inwardly onto the folded ends and partitions 20 or onto each other, depending upon whether the width is greater or less than twice the height of the crate. The side strips formed by the sections 25 and 26 are then "broke" inwardly, the sections swinging upon the hinges 27, 28 and 29 until they have their outer faces contacting, as clearly shown in Fig. 6. This folding of the sections 25 and 26 results in or is accomplished by moving the top frame toward the bottom frame. When the device is fully collapsed the top frame will lie immediately above the bottom frame and the device will have but little height. The cover 18 is then swung onto the top frame, after which the wires 19 are engaged within screw eyes 32 extending from the end strips 12 and one side strip 11 of the bottom frame, as clearly shown in Fig. 4. The parts will thus be held in folded position.

From the foregoing description and a study of the drawings it will be apparent that I have thus provided a very simply constructed shipping box or crate which may be very readily extended for use and as easily collapsed or folded so as to occupy the minimum space.

While I have shown and described the preferred embodiment of my invention, it is of course to be understood that I reserve the right to make such changes in the form,

construction, and arrangement of parts as will not depart from the spirit of the invention or the scope of the subjoined claims.

Having thus described my invention, I claim:—

1. A collapsible shipping box comprising a bottom frame, an open top frame, a cover hinged upon and forming a closure for said top frame, end walls hinged upon said bottom frame and swingable to lie selectively upon said bottom frame or in engagement with the inner faces of the ends of said top frame, means for holding said end walls in engagement with said top frame, side panels hinged upon said bottom frame and swingable to be folded onto said folded end walls or to lie against the inner faces of the sides of said top frame, means for holding said side panels against inward folding, and side strips each formed in two sections hingedly connected at their centers for inward collapsing and having their ends hingedly connected with said top and bottom frames.

2. A collapsible shipping box comprising a bottom, side and end strips secured to and extending upwardly from said bottom for forming a frame, an open rectangular top frame of the same dimensions as said bottom frame and including side and end strips, end walls hinged upon the end strips of said bottom frame and engaging the inner faces of the end strips of the top frame, turn buttons carried by the end strips of the top frame and engaging said end walls, side panels hinged upon the side strips of the bottom frame and engaging against the inner faces of the side strips of the top frame outwardly of the edges of said end walls, and a plurality of strips formed in sections hingedly connected at their centers and hingedly connected at their ends with the sides of said top and bottom frames, said end walls and said side panels being foldable inwardly and said hinged strips being breakable inwardly whereby said top frame may lie directly upon said bottom frame.

In testimony whereof I affix my signature.

C. O. SHEPHERD.
